TAPPER FOR BAR LIQUOR DISPENSER SYSTEM

Samuel W. Neidorf, Los Angeles, and Chester H. Haynoski, Granada Hills, Calif., assignors to Bar-O-Matic Sales Co., Van Nuys, Calif.

Filed June 13, 1969, Ser. No. 17,700

Term of patent 14 years

Int. Cl. D15—12

U.S. Cl. D94—3

FIG. 1 is an exploded view of the tapper for bar liquor dispenser system embodying our new design;

FIG. 2 is a front elevational view thereof;

FIG. 3 is a side elevational view thereof;

FIG. 4 is a sectional view thereof taken on line 4-4 of FIG. 2;

FIG. 5 is a sectional view thereof taken on line 5-5 of FIG. 2;

FIG. 6 is an exploded view of a second embodiment of our new design;

FIG. 7 is a front elevational view thereof;

FIG. 8 is a side elevational view thereof;

FIG. 9 is a sectional view thereof taken on line 9-9 of FIG. 7; and

FIG. 10 is a sectional view thereof taken on line 10-10 of FIG. 7.

The additional tubing is shown in broken lines in FIGS. 2 and 7 as environmental structures.

We claim:

The ornamental design for a tapper for bar liquor dispenser system, substantially as shown and described.
